DESIGN FOR A LOUNGING CHAIR

Karl Kipp, Olean, N. Y., assignor to Daystrom Corporation, Olean, N. Y., a corporation of New York

Application May 19, 1948, Serial No. 146,457

Term of patent 7 years

(Cl. D15—1)

To all whom it may concern:

Be it known that I, Karl Kipp, a citizen of the United States, residing at Olean, in the county of Cattaraugus and State of New York, have invented a new, original, and ornamental Design for a Lounging Chair, of which the following is a specification, reference being had to the accompanying drawing, forming part thereof; and in which

Fig. 1 is a perspective view of a lounging chair showing my new design; and

Fig. 2 is a rear elevational view thereof.

I claim:

The ornamental design for a lounging chair, substantially as shown.

KARL KIPP.
